SAW ATTACHMENT FOR PORTABLE ELECTRIC DRILLS

Eugene J. Majewski, Chicago, Ill., assignor to
Portable Electric Tools, Inc., Chicago, Ill., a cor-
poration of Illinois

Application March 7, 1952, Serial No. 18,816

Term of patent 14 years

(Cl. D93—3)

To all whom it may concern:

Be it known that I, Eugene J. Majewski, a citizen of the United States, residing at Chicago, in the county of Cook and State of Illinois, have invented a new, original, and ornamental Design for a Saw Attachment for Portable Electric Drills, of which the following is a specification, reference being made to the accompanying drawings forming a part hereof.

In the drawings:

Fig. 1 is a top plan view of a saw attachment for portable electric drills showing my new design;

Fig. 2 is a side elevational view of the saw attachment;

Fig. 3 is a bottom plan view thereof;

Fig. 4 is a rear elevational view; and

Fig. 5 is a front elevational view thereof.

The other side of the saw attachment as shown in Fig. 2 is substantially identical with that side shown in Fig. 2 with the exception of the stub shaft.

I claim:

The ornamental design for a saw attachment for portable electric drills, substantially as shown and described.

EUGENE J. MAJEWSKI.
